(57) **CLAIM**

The ornamental design for a bottle, as shown and described.

DESCRIPTION

FIG. 1 is a perspective view of a first embodiment,

FIG. 2 is a front view thereof,

FIG. 3 is a rear view thereof,

FIG. 4 is a bottom view thereof,

FIG. 5 is a top view thereof,

FIG. 6 is a right-side view thereof, and

FIG. 7 is a left-side view thereof;

FIG. 8 is a perspective view of a second embodiment,

FIG. 9 is a front view thereof,

FIG. 10 is a rear view thereof,

FIG. 11 is a bottom view thereof,

FIG. 12 is a top view thereof,

FIG. 13 is a right-side view thereof, and

FIG. 14 is a left-side view thereof; and

FIG. 15 is a perspective view of a third embodiment,

FIG. 16 is a front view thereof,

FIG. 17 is a rear view thereof,

FIG. 18 is a bottom view thereof,

FIG. 19 is a top view thereof,

FIG. 20 is a right-side view thereof; and,

FIG. 21 is a left-side view thereof.

The broken lines are included for the purpose of illustrating a portion of the bottom that forms no part of the claimed design.
